UNITED STATES PATENT OFFICE.

WILLIAM P. LOCKE AND HENRY D. MINNICK, OF CANTON, OHIO.

SIPHON.

SPECIFICATION forming part of Letters Patent No. 773,511, dated October 25, 1904.

Application filed March 1, 1904. Serial No. 196,082. (No model.)

To all whom it may concern:

Be it known that we, WILLIAM P. LOCKE and HENRY D. MINNICK, citizens of the United States, and residents of Canton, in the county of Stark and State of Ohio, have made certain new and useful Improvements in Siphons, of which the following is a specification.

Our invention is an improvement in that class of siphons which are provided with a starting attachment consisting of air-exhausting mechanism. In our invention the liquid is received into a chamber which is provided at one end with a collapsible bulb and at the other with an outlet-valve, other valves being provided for controlling the escape of air.

The invention is embodied in the construction, arrangement, and combination of parts hereinafter described, reference being had to the accompanying drawings, in which—

Figure 1 is a central longitudinal section of the main portion of our improved siphon attachment, the same being shown applied to a bottle or other receptacle for liquid. Fig. 2 is a view illustrating the arrangement of the siphon in practical use. Fig. 3 is a central longitudinal section illustrating the operation of the main portion of the apparatus when air is being extracted from the siphon-tube and receiving-chamber. Fig. 4 is a similar section showing the position of certain parts when liquid has been received into the chamber and is discharging therefrom. Figs. 5 and 6 are perspective views illustrating means for locking a spring-valve contained within the liquid-receiving chamber and serving to control the escape of air. Fig. 7 is a plan view of the device employed for supporting the siphon attachment upon a bottle. Fig. 8 is a perspective view of the device employed for supporting a siphon-hose in the holder from which the liquid is drawn.

Referring in the first instance to Fig. 1, A indicates the liquid-receiving chamber with which the flexible hose B is connected. (See also Fig. 2.) The said chamber is provided with screw-caps a and a' at its respective ends. The upper cap a has a tubular extension a^2 , to which a collapsible bulb C is attached. As shown, the extension a^2 has a circumferential 50 corrugation or rib for holding the bulb se-

curely attached and also an opening a^3 at its upper end. The lower cap a' is dished or concaved to permit the outflow of liquid and provide a seat for an elastic washer d, which is attached to the outlet-tube D. The latter is 55 adapted to fit neatly but also slide in the tubular extension a^4 of the cap a' . The aforesaid washer d is secured by a screw to the thickened head of the tube D, and the latter is provided with a series of adjacent openings d' , 60 through which the liquid escapes from the chamber A when the valve or tube D is raised in the position shown in Fig. 4. Between the flange a^5 of the tubular extension of the chamber A and a cross-piece or "spider" E, 65 which is fixed in the tube D and in use rests upon the neck of the bottle or other receptacle Y for the liquid, is arranged a spiral spring F, which encircles the tube D, as shown. The said cross-piece E (see Fig. 7) has radial 70 arms, as shown, and one of them is provided with a spring-catch G, which is adapted to engage the flange a^5 in a certain contingency, as will be hereinafter explained.

Within the tubular extension a^2 of the chamber A is secured a centrally-perforated plug a^6 . In the upper end of the same is located a check-valve H, which seats downward. The upper end of the bulb C is provided with a similar valve I, which also seats downward 80 and prevents inlet of air at that point, while allowing its free escape.

Within the chamber A is arranged a valve mechanism for closing the lower end of the bored plug a^6 . This, as shown, (see especially 85 Figs. 1, 5, 6,) consists of a valve proper, J, and spring-support K. The said support is formed of a plate-spring so bent that it has two horizontal members, the upper one having an opening k, which adapts it for attachment to the lower end of the plug a^6 , and the lower one a smaller opening k' , which provides for attachment of the valve proper, J. The free end of the upper member of the spring is bifurcated and bent downward, and a plate-lever L is suspended and adapted to rock therein by means of an axis l. (See Fig. 5.) The upper end of the plate-lever L is curved outwardly and provided with a horizontal opening l', which is adapted to receive 100

the end k^2 of the lower member of the spring K. The arrangement is, however, such that this engagement can take place and be maintained only when the plate-lever L is in vertical position or adjusted to the right of such position, as shown in Figs. 1, 3, 4. In other words, when the lever L is thrown to the left, as indicated by dotted lines, Fig. 4, it is disengaged from the valve-spring K, as will be readily understood.

A device M, which may be termed a "button," is arranged in connection with the upper cap a of the liquid-receptacle for throwing down the lower member of the spring K for the purpose of removing the valve J from its seat, as indicated in Fig. 3, and at the same time locking the valve-spring in engagement with the plate-lever L. The said button consists of a push-rod which slides in a suitable holder, its lower end resting upon the lower member of the spring K and its upper end being enlarged to form a head. Between the said head and the holder in which the rod slides is a spiral spring m , that serves to hold the device normally elevated, as shown in Figs. 1 and 4.

We will now describe the operation of the apparatus. By pushing the button M downward the lower member of the spring K is forced downward until its end engages the notch or slot l^1 in the lever L. Thus the valve J is removed from its seat and held removed by the locking engagement of the spring with the part L. It is apparent that the curved form of the upper portion of the valve-lever L enables this engagement to be easily effected, the part L swinging on its axis as required for the purpose. The free end of the hose B having been first immersed in the liquid-holder X, (see Fig. 2,) the bulb C is squeezed and thereby collapsed, (see Fig. 3,) and then being allowed to expand the air contained in the hose B and the chamber A is drawn out through the passage provided by the parts a^6 and a^2 into the bulb-chamber, as indicated by arrows. By squeezing the bulb a second time and allowing it to expand it is again refilled with air, and this may be repeated, if necessary, for the purpose of thorough exhaustion of air, whereupon the liquid will begin to flow from the receptacle X and fill the chamber, as indicated in Fig. 4. In entering the chamber the liquid exerts sufficient force to throw the lower end of the lever L to the left or away from the mouth of the inlet a^7 , whereby the lower member of the spring K is released and the valve J allowed to resume its seat on the plug a^6 , thus closing the latter, so that no liquid can be sucked into the bulb. The body of the chamber A may be made of glass, in which case the operator may readily perceive the height of the liquid therein; but he will be apprised when the chamber is filled by reason of the fact that the bulb C does not readily expand,

and this indicates that the siphon is ready for continuous action. The end of the tube D is then inserted to the cross-piece or spider E, the cross-piece resting upon the bottle or other holder which it is desired to fill. Then by downward pressure upon the body of the chamber the tube D is forced upward through the tubular extension a^4 of the chamber A, as shown in Fig. 4, so that the openings d' of tube D are carried above the cap a' . It is apparent that when the parts are held in this position the liquid will flow continuously so long as any liquid remains in the holder. In other words, the liquid will continue to flow so long as the air-pressure on the body of liquid in X is maintained. Since it would be somewhat inconvenient to maintain this pressure upon the spring F for holding it compressed, as indicated in Fig. 4, the spring-catch G will be engaged with the flange a^5 , as there indicated. When the receptacle Y has been filled, a slight downward pressure upon the chamber will release the spring G from engagement, and the chamber being allowed to rise by the expansion of the spring F the washer d will again seat, as shown in Figs. 1 and 3, and the flow of liquid from the chamber be thus cut off. It is obvious that the apparatus may then be applied to another receptacle and the operation repeated at will, or the apparatus will remain indefinitely ready for immediate flow whenever required. It is further apparent that the bulb need not be again manipulated, since the chamber will remain fully charged so long as the free end of the hose B is immersed in the supply-tank or holder X.

A small opening d^2 is provided in the tube D at such a point that when the latter is in the normal position, as shown in Figs. 1, 3, air is admitted to induce perfect drainage of the tube D. Without this provision a certain amount of liquid, more especially if the same be of a viscid nature, would be retained in the tube and drip slowly out and go to waste.

It will be seen that by our improved apparatus the liquid is never admitted to the bulb. The free end of the hose B is provided with a perforated tube b (see Fig. 2) for the purpose of preventing any solid matter being drawn in.

In Figs. 2 and 8 we illustrate an improved device N for supporting the hose B in the liquid holder or tank X. It is formed of spring-wire and its general form approximates that of the letter V. There is a central coil adapted to receive and embrace the hose B, and each of the two divergent arms has two outwardly-projecting shoulders, which are formed by bends of the wire. It will be seen that these shoulders serve to prevent the device moving upward or downward when duly adjusted in position, as shown in Fig. 2. When the arms are pressed toward each other, the device will slide easily on the hose; but when allowed to

expand the coil tightens on the hose and the latter is held with sufficient friction to prevent its sliding in the holder.

What we claim is—

- 5 1. The improved siphon attachment comprising a liquid-receiving chamber, a collapsible bulb applied thereto and valves permitting the outflow of air and preventing the flow of liquid into the bulb, an outflow-valve connected with the chamber, and a valve arranged within the chamber and serving to close the outlet to the bulb, and means for unseating said valve as required for starting the siphon, substantially as described.
- 15 2. The improved siphon attachment, comprising a liquid-receiving chamber, a collapsible bulb applied thereto and provided with a valve which permits the outflow of air and prevents the inflow of the same, a second valve arranged within the said chamber and adapted to close the air-outlet thereof, and means accessible exterior to the chamber for manipulating and unseating the interior valve, to allow the escape of air from said chamber, substantially as described.
- 25 3. In a siphon attachment of the class indicated, the combination, with a liquid-receiving chamber, a collapsible bulb connected therewith, and provided with suitable air-valves, of a valve arranged within the chamber for closing the air-outlet to the bulb, and a trip device connected with said valve and adapted to be acted upon by the liquid entering the chamber, substantially as described.
- 35 4. The improved siphon attachment comprising the liquid-receiving chamber A having a valved outlet, a collapsible bulb, and valves for controlling the ingress of air, and a valved attachment arranged within the chamber and comprising a spring-holder to which a valve proper is attached, the same being adapted to normally close the air-outlet, and means for manipulating and unseating said valve and means for automatically locking it in the unseated position, substantially as described.
- 45 5. The improved siphon attachment comprising a liquid-receiving chamber, a valved outlet, a collapsible bulb having suitable air-valves, and mechanism arranged within the chamber and comprising a valve adapted to close the air-outlet, a spring to which said valve is attached, a button or pusher which is accessible exterior to the chamber and adapted to act on the valve-spring for forcing the

valve away from its seat, and means for automatically locking the spring, the same being adapted to be actuated by the inflow of liquid for releasing the spring, substantially as described.

6. The improved siphon attachment comprising the liquid-receiving chamber having a valved outlet, a collapsible bulb and valves controlling the air-passages, and a mechanism arranged within the chamber and comprising a valve adapted to close the air-outlet, a spring-support and carrier therefor, a movable device adapted for automatic engagement with the spring and for holding the latter expanded so that the valve is held away from its seat, the said device being normally pendent in front of the mouth of the liquid-inlet and adapted to be acted upon by the flow of the liquid, whereby it is thrown into such position as to release the spring and to allow the valve to close automatically, substantially as described.

7. The improved siphon attachment comprising the liquid-receiving chamber having a valved outlet, a collapsible bulb having air-valves, and the valve mechanism arranged within said chamber and comprising a valve for closing the air-outlet, a bifurcated spring to which the valve is attached, a swinging plate-lever which hangs normally in front of the liquid-inlet and is provided at its upper end with a slot adapted for engaging with the free end of the valve-spring support, and a device, which is accessible exteriorly of the chamber, for forcing the valve-spring downward into locking engagement with the lever, substantially as described.

8. In a siphon attachment, the combination, with a liquid-receiving chamber having outlets for escape of air and liquid, of the mechanism arranged therein comprising a valve adapted to close the air-outlet, a spring-support therefor, means for locking the spring in position to hold the valve unseated, and means adapted to be acted upon by the inflowing liquid for releasing the spring, and a device which is accessible exteriorly to the chamber for setting the valve in the locked position, substantially as described.
